UNITED STATES PATENT OFFICE

FRANK W. STEERE, OF NEW YORK, N. Y., ASSIGNOR, BY MESNE ASSIGNMENTS, TO YOUNG-WHITWELL GAS PROCESS COMPANY, OF TACOMA, WASHINGTON, A CORPORATION OF WASHINGTON

WATER-GAS APPARATUS

Application filed May 7, 1923, Serial No. 637,159. Renewed August 6, 1927.

The invention relates to a gas making apparatus and is designed as an improvement upon the invention of D. J. Young described in his applications for patent on Apparatus and process for making illuminating gas, Ser. No. 477,365, filed June 14, 1921, Patent No. 1,468,190 and Ser. No. 570,207, filed June 22, 1922.

One of the important objects of the invention is to provide an improved means for passing steam through the water gas plant as a whole, the steam being introduced at the top of the superheater, becoming superheated in passing through the superheater and carburetter and being, therefore, placed in the most favorable condition to react with the fuel in the generator for the manufacture of water gas.

Another object of the invention is to provide an unobstructed passage from the generator to the wash-box. Heretofore expensive valves which are easily fouled have been interposed in this passageway. The elimination of these valves results in a decreased capital and maintenance saving.

A further object is to provide an improved means for superheating the backrun steam within a one, two, or three shell set. Heretofore the so-called "down run" steam has not been superheated or has been heated only by means of expensive external equipment or additional shells. The improved apparatus which eliminates these defects, results, therefore, both in a fuel saving and a capacity increase.

A further object is to provide means by which the checkerbrick in the carburetter and superheater may be kept clean. Heretofore these have become fouled, even when using a high grade oil, after as little as 1200 hours of operation. The improved device is operated with decreased maintenance cost and admits of the use as an enricher of the cheaper low grade oils.

The invention further provides an improved means for reversing the flow of steam throughout the entire one, two, or three shell set without the obligatory use of valves. The present apparatus is simpler, the operating costs are less, and there is much

greater ease of both operation and maintenance.

Another important advantage of the present device is that it is adapted to burn any generator fuel. Heretofore the use of bituminous coal has been difficult because the carburetter and superheater soon became clogged. The present apparatus is adapted to burn coal as well as coke without clogging, and the result is, therefore, a reduced fuel cost.

A further and very important object of the invention is to provide means for recirculating the backrun blue water gas through the entire set. By now increasing the volume of gases circulated through the machine a greatly increased capacity is attained with a consequent decrease in the cost of manufacturing the gas.

The present invention is applicable with but slight modifications to many existing carburetted water gas equipments. This reduces the cost of installing the system in an existing plant to a minimum and makes the wide use of the backrun possible.

Further objects of the invention from the description and claims which follow will appear.

The invention may be more clearly understood by reference to the accompanying drawings in which are shown an illustrative embodiment of the invention, it being understood that many changes in detail may be made without departing from the spirit of the invention.

In the drawings:

Fig. 1 is a view showing a water gas plant, parts being shown in vertical section and parts in elevation.

Fig. 2 is a top plan view of the plant.

Referring first to the apparatus shown in the drawings, the shells designated by the reference characters A, B, and C, are respectively the water gas generator, carburetter, and superheater, of a carburetted water gas set. They may be arranged as shown or the carburetter and superheater may be combined in one shell or all three shells may be superimposed, or any other desired ar-

85

100

angement may be employed. D is the wash-box.

Generator A is provided with the usual fuel charging door A' and with grates A'', upon which the fuel rests as shown. There are clean-out doors under the grates (not shown).

Carburetter B is filled with checkerbrick as shown. It is provided with an oil spray 13 U controlled by valve V through which oil may be introduced.

Superheater C is filled with checkerbrick as shown. It also has a stack-cap Z.

Between the generator A and carburetter B, there is an opening or connecting passage W, which is not obstructed in any way by a valve or other device. Between the carburetter and superheater there is a similar opening or connecting passage Y, similarly unobstructed.

Leading into the base of the generator A, under the grates A'' is a pipe E through which air controlled by the valve F may pass. A similar air pipe G provided with valve H 25 leads to the top of the carburetter. A third air line might lead to the bottom of the superheater (not shown).

Also below the grates A'' in the generator A there is introduced a pipe N provided with 30 a valve P. This pipe is known as the backrun gas pipe. Similarly, from the top of the superheater C, there leads a gas offtake pipe, N'. Offtake pipe N' connects with backrun pipe N at S. S may be a T or cross or other 35 suitable connection. From S a single pipe T leads to the wash-box D. Pipe N' may be provided with a butterfly or other valve if desired or required. Such a valve is not shown in the drawing. When the valve is not used 40 there is, therefore, a free and unobstructed main passage from under the grates A'', through A, W, B, Y, C, N', S, and T, to the wash-box D.

A by-pass connection R is placed between 45 offtake pipe N' and backrun pipe N. This by-pass R is inserted ahead of the connection S which has also been described as connecting pipes N and N'. By-pass R may be curved as shown or of any other shape suitable to the function performed by this by-pass as hereinafter described.

In the by-pass R is introduced a steam-line as shown at K. Steam flow is controlled by valves L. The steam-line K terminates in 55 the nozzle M as shown.

Another steam-line shown as I is introduced under the grates A'' in the generator A. Steam flow through this line is controlled by the valve J.

60 In operating this set many procedures are at once apparent to those versed in the art. One method, known as the split-run, will be described.

The generator A is filled with fuel which 65 may be any solid fuel in any state of division,

that is common to or possible of use in the manufacture of water gas. All valves except F, H, and Z, are closed. If line N' is equipped with a valve, it remains open. The air passing into the generator and under the grates therein enters into primary combustion with the generator fuel. The air admitted to the top of the carburetter (and the bottom of the superheater, if so desired) enters into secondary combustion with the products of the primary combustion. The final combustion products pass out at the superheater stack Z. The result of this operation, which is known as the air blasting, is that the fuel bed in the generator is heated to incandescence and the checkerbrick in the carburetter and superheater have large quantities of heat stored in them. Blasting may be continued for as long as necessary, usually two or three minutes.

At the end of the blast, valve J is opened, and valves F, H, and Z, closed. Valve V may also be opened. Steam is now being admitted at the base of the generator. Passing up through the fire-bed, it is decomposed, forming blue water gas containing principally hydrogen, carbon monoxide, a little carbon dioxide, and a small quantity of other constituents. The blue water gas passes into the top of the carburetter through the passage W. If valve V is open oil is being admitted to the carburetter where the heat there stored cracks and vaporizes the oil into a combination of gases, in large part, hydrocarbons. This oil gas mixed with the blue water gas 100 becomes fixed as the gases pass down through the carburetter, through the passage Y, up through the superheater, through the pipes N' and T (some gas perhaps passing through R and N) and into the wash-box, from whence they pass through a suitable pipe T' to whatever place is desired. Such procedure is known as an up-run. The up-run may be continued as long as desirable. At its termination, valves J and V are closed and valves 110 P and L opened. If used the valve in N' is closed. A backrun is now starting. Steam admitted through the nozzle M passes through by-pass R into offtake pipe N' and thence into the top of the superheater, down through the superheater, through the passage Y and up through the carburetter and passage W into the top of the generator.

In so doing, the steam has become superheated by heat transfer from the checkerbrick. Furthermore, by mechanical and chemical action, this steam has removed from the checkerbrick such ash and carbon as may have become deposited on them. Finally the checkerbrick, particularly at the top of the superheater, has become cooled.

The steam at the generator passes down through the incandescent firebed and becomes decomposed into blue water gas which passes out at the base of the generator into 130

the backrun pipe N and thence through pipe T into the wash-box.

The introduction of steam at M, however, in this manner causes a portion of the gas in the backrun pipe N to be by-passed through the pipe R from whence it accompanies the steam and is recirculated through the set. This recirculation depends upon the extent of the injector action of the steam flowing through the nozzle M, upon the velocity heads of the various gases involved and upon the pressure conditions in the set. The act of recirculation, however, has a most important and beneficial effect upon the economical operation of the set in the manufacture of carburetted water gas.

First, a larger volume and weight of gases is passed through the superheater and carburetter than if steam alone were so passed, thereby transferring to the generator where it can do useful work the heat contained in the superheater and carburetter, which would be otherwise wasted.

Second, when blue water gas is passed a second time through the firebed, the carbon dioxide contained therein is afforded another opportunity to become reduced to the more valuable carbon monoxide.

Third, the capacity of the set is greatly increased as will be shown in the following discussion. When steam reacts with incandescent carbon, two main reactions are possible according to the temperature and concentration of the reacting substances.

The first of these two is the one most desired in making carburetted water gas.

Maximum capacity, among other things, requires maximum passage of steam. The amount of steam possible to be used, however, is limited by a further reaction.

Too much steam, therefore, has heretofore resulted in the formation of carbon dioxide, so undesirable as to limit the amount of steamisable and, with it, the capacity of the set.

Recirculation of considerable portions of the backrun gas permits the use of excess steam and the attainment of increased capacity because when carbon dioxide is formed, it is later reduced to carbon monoxide by again passing through the firebed and coming in contact with incandescent carbon, thus

With this understanding of the backrun, a further description of the operation may be made. When the backrun has proceeded for such length of time as may be desirable, for instance, two minutes, valves P and L are closed and valve J opened. If used, the valve in N' is opened. Another steam up-run

is now in operation. Valve V may be opened and oil admitted but this procedure on this up-run is not preferred. This up-run continues as desired, preferably for from 5 to 15 seconds, when the fire-bed has become so cooled from the endothermic reactions due to the passage of steam, that the air blast must be again used. Valve J is therefore closed and valves F, H, and Z, opened. The cycle can now be repeated.

The operation as herein outlined is merely an example. It is clear that the air blast may be followed by a steam up-run, which is immediately followed by another blast, or the blast may be followed by a steam backrun, then by an up-run and the blast then put on. Any cycle that seems desirable may be used. The split-run, as here described, is merely preferable.

Fuel may be charged into the generator every five or six cycles, or after any number of runs as seems desirable. It may, if means are provided, be charged continuously.

The oil admitted to the carburetter to be vaporized, cracked, and fixed, as oil gas to carburet the blue water gas, may be of any quality because of the cleansing action of the backrun steam on the checker-brick.

The improved apparatus is adapted to be used cheaply in all existing carburetted water gas equipment, slight modifications only being required. This reduces the cost of installing the system in an existing plant and makes the wide use of the backrun possible.

The invention results further in a reduction of sensible heat loss. Heretofore the gases, both on blast and make, have left the superheater at 1300° to 1400° F. According to the present apparatus they leave the superheater on the forward run at 900° to 1000° F. and on the backrun they leave the base of the generator at 200° to 300° F. These low temperatures of the outgoing backrun gases materially decrease the subsequent cooling problem with respect to these gases.

It is obvious that many changes in various details may be made without departing from the spirit of the invention the scope of which is to be limited only by the appended claims.

For example, a two shell instead of a three shell set may be used or the number of shells may be increased beyond three, if desired. Furthermore, while the best results have in practice been obtained by locating the steam jet M beyond the superheater of a three shell set as herein shown and described, the jet may be located beyond the carburetter if desired or in a set of more than three shells it may be located just beyond any particular one of the shells.

It will also be noted that the jet M is not directed toward the generator or toward any one of the shells but is directed at an angle to the offtake passage of the adjacent shell, as the passage N' in the construction shown.

This arrangement facilitates the withdrawal of a portion of gas from the backrun pipe N without interfering with the flow of the remainder to the wash-box D. It also permits of the passage of all of the admitted steam in a direction away from the wash-box.

It will be understood that in the claims the term "heat interchanger" refers to the carburetter or superheater or both.

10 I claim:—

1: A water gas set including a generator and a heat interchanger containing heated checkerwork connected in series by a free and unobstructed main passage, a second passage leading from the generator to a gas offtake, and a by-pass connecting the said passages, said by-pass having a steam jet therein adapted to deliver steam in a direction at an angle to the normal gas flow through the main passage.

2: A carburetted water gas set including a generator, carburetter, and superheater, connected in series by a free and unobstructed main passage, a second passage leading from the generator to a gas offtake, and a by-pass connecting the said passages, said by-pass having a steam jet therein adapted to deliver steam in a direction at an angle to the normal gas flow through the main passage.

3: A water gas plant having a main passage leading from a generator through a carburetter and a superheater to a gas offtake, a second passage leading from the generator to the gas offtake, a by-pass connection between said main passage and said second passage, and a steam jet located in said by-pass.

4: A water gas set including a generator and a superheater, a main passage leading from said generator through the superheater to a gas offtake, a second passage leading from the generator to said offtake, a by-pass connection between said main passage and said second passage, and a steam jet located in said by-pass adapted to deliver steam in a direction at an angle to the normal flow of gas through the main passageway.

In testimony whereof I hereunto set my hand this 2nd day of May, 1923.

FRANK W. STEERE.
